UNITED STATES PATENT OFFICE.

JEROME WHEELOCK, OF WORCESTER, MASSACHUSETTS.

EXHAUST INJECTOR-CONDENSER.

SPECIFICATION forming part of Letters Patent No. 242,089, dated May 24, 1881.

Application filed March 21, 1881. (No model.)

To all whom it may concern:

Be it known that I, JEROME WHEELOCK, of the city and county of Worcester, in the State of Massachusetts, have invented certain new and useful Improvements in Exhaust Injector-Condensers for Steam-Engines; and I do hereby declare that the following specification, taken in connection with the drawings furnished and forming a part of the same, is a clear, true, and complete description of my invention.

In the operation of condensers of this class it frequently becomes desirable to permit the free exhaust from the engine unfettered by the throttling of the steam incident to exhaust condensers as heretofore constructed, and during such times the water in the hot-well becomes objectionably reduced in temperature, and the prime object of my improvement is to provide for heating water from the hot-well or other desirable source, on its way to the boiler, regardless of the operation of the injector-condenser, and incident to the attainment of that end I also, to a greater or lesser extent, reduce the work of condensation, which the injector has heretofore been wholly relied upon to perform.

Briefly stated, my invention consists in the combination, with the exhaust injector-condenser, of a stack or coil of water-pipe located within the uptake or exhaust-pipe of the condenser and communicating with the hot-well and boiler via the boiler-pump.

I am, of course, well aware that exhaust-steam has heretofore been employed within apparatus of various kinds for heating feed-water for boilers, and it is to be understood that my said improvement is limited to an apparatus embodying as a part thereof an exhaust injector-condenser.

To more particularly describe my invention, I will refer to the accompanying drawings, illustrating in section my improvements, as embodied in what I recognize as a siphon-exhaust injector-condenser, in which the exhaust-steam from the cylinder A enters and passes upward within the uptake or exhaust-pipe B, thence curves over and downward, through the injector C, provided with a detachable nozzle, a, in accordance with an improvement heretofore patented by me. The lower end of the pipe b below the condenser enters the usual hot-well, (not shown,) or it may be located directly over, but above the mouth of said well, if desired. The water-pipe D at one end enters the hot-well below the water-line thereof and en-

ters the exhaust-pipe B at its base through the base-plate c, extends upward therein preferably to the height of the curve at its upper end, and thence is returned downward, either by a coil or in a straight line, and doubled on itself as many times as may be deemed desirable in each case, and finally leaves said exhaust-pipe at its base, and from thence extends to the boiler via the boiler-pump. (Not shown.) Under all circumstances the feed-water on its way to the boiler is heated in its passage within the exhaust-pipe, and in proportion to the temperature of said water from the hot-well more or less condensation is effected within the exhaust-pipe B, and I therefore prefer to provide a small pipe, d, which enters the foot of the exhaust-pipe through the base-plate c and communicates with the hot-well for the direct passage of such waters of condensation as may from time to time be developed by the low temperature of the feed-water pipe D.

It will be seen that if the water-supply of the condenser C be at any time cut off, or so far reduced in quantity as to fail to maintain the water in the hot-well at a desirable temperature for feeding to the boiler—as, for instance, when it is desirable to permit free exhaust—nevertheless by my construction the feed-water on its way to the boiler will be properly heated.

The internal dimensions of the exhaust-pipe B being proportionably spacious according to the bulk of the feed-water pipes D renders the latter no obstruction to a free exhaust, and the steam, being more or less reduced in temperature by said feed-water pipe, is more readily further condensed at the condenser C than would be the case if said feed-water pipes were not present. Although I have shown and prefer that the exhaust-pipe B be vertical in its position, it is obvious that it may be inclined or horizontal, and that the condenser may be variably arranged relatively to said pipe.

Having thus described my invention, I claim as new—

The combination, with an exhaust injector-condenser, of a coil of pipe within the exhaust-pipe, traversed by the feed-water on its way from the hot-well or other source to the boiler, substantially as described.

JEROME WHEELOCK.
